ANTI-ANEMIA MATERIAL AND METHOD OF
MAKING THE SAMEWilliam S. McEllroy and William F. Herron,
Pittsburgh, Pa.No Drawing. Application June 30, 1932,
Serial No. 620,301

10 Claims. (Cl. 167—74)

This invention relates to methods of treating glands and tissue to produce highly concentrated, potent preparations for use in the treatment of disease. Specifically, this invention relates to a method of treating animal material, such as fresh beef or calf liver, to increase the available therapeutically potent materials or substances contained therein.

An object of the invention is to produce a liver derivative for the treatment of anemia, which contains the preformed therapeutically potent material of fresh raw liver and also therapeutically potent material potential in fresh liver, but heretofore unavailable as a liver derivative.

Five years ago or more, Minot observed that the taking of raw, or partially cooked, whole liver, daily by persons suffering from pernicious anemia, produced remission of the disease, and that improvement took place about the tenth day. In order to produce remission, the patient had to consume a minimum of approximately three thousand grams, or roughly, 6.6 pounds of raw or partially cooked liver. After remission, the patient was required to take, daily, approximately $\frac{1}{4}$ pound, more or less, of liver, depending upon the condition of the patient, in order to maintain the patient in a healthy condition. Such a sustained diet of liver was, in most cases, impossible to maintain because the patient could not retain it in his stomach. Because of this revulsion of the body to a sustained liver diet, concentrated potent preparations of liver were developed.

Some of these preparations were adapted to be taken by mouth and others for intramuscular injection. These highly concentrated forms of liver overcame, to a large extent, the objection of a sustained diet of raw or partially cooked liver.

It has been observed that fresh liver, for example calf's liver, contains a relatively small amount of preformed materials that are beneficial in the treatment of pernicious anemia. If raw or partially cooked liver is taken by a patient suffering from this disease, these preformed materials produce remission, as indicated by increase of the reticulocytes of the patient's blood. Since it was found that a patient could not endure a sustained diet of raw or partially cooked liver, methods were developed whereby concentrated potent preparations of liver could be produced having the preformed materials therein. Some of these preparations were made in powdered form and others in extract or liquid form.

Since calf's liver contains more of these pre-

formed materials than adult or beef liver, calf's liver has been the chief source of supply of raw materials for the production of preparations which are potent in respect to the beneficial preformed materials of liver, and being therefore in demand has become very expensive and has made these potent preparations very expensive, also.

The most generally utilized method of producing the above mentioned potent preparations of liver, is the one devised by Minot and Cohn. Under this method, the preformed materials are derived by a chemical process involving a series of steps depending on differential solubilities of a series of solvents, the last step producing what is known as fraction G which is soluble in water but insoluble in 95% alcohol. Fraction G contains only the preformed active materials, present in liver, in concentrated and potent form which produces remission in the treatment of pernicious anemia. By these methods, only the preformed potent materials are made available for therapeutic action and such available preformed materials are only a nominal percentum of the potential supply thereof.

In the light of our researches and observations, we have discovered that the largest proportion of the potent materials in liver which are useful and beneficial in the treatment of pernicious anemia, are bound up in an unavailable form. This large potential supply of beneficial materials is unavailable to the patient, if liver is taken in raw or partially cooked form, because the patient's digestive system cannot liberate or extract them.

This large potential supply of beneficial material has also been unavailable in the concentrated forms because the methods heretofore used for preparing concentrated and potent products of liver will not release or yield any of these bound up materials from their potential source of supply.

At the present time, the identity and the quantity of the therapeutically active materials present in these potent preparations cannot be determined by chemical analysis, because, apparently, these active, beneficial materials are destroyed in the process of analysis. Therefore, the only method, now known, of determining the amount of these potent, beneficial and therapeutically active materials present in a given preparation, is by biological assay. In other words, the preparation is fed to a patient until remission occurs, and the amount required to invoke remission is a measure of the potency of the preparation.

An object of our invention is therefore to provide a method whereby this large potential supply of therapeutically active materials may be released from glands and tissue and be converted into therapeutically potent material and thus made available for the treatment of disease.

Another object of our invention is the provision of a method of treating liver or tissue so that the large supply of beneficial materials therein, which are otherwise bound up in unavailable form, may be liberated and made available for the treatment of diseases such as pernicious anemia.

Another object of the invention is the provision of a method whereby adult liver or tissue may be treated in such manner as to yield larger quantities of beneficial materials useful in the treatment and remission of pernicious anemia, than it has heretofore been possible to obtain from calf's liver by methods of the prior art.

A still further object of our invention is the provision of a method of producing highly potent preparations for the treatment of disease such as pernicious anemia, that shall be inexpensive, within the means of the rich and the poor, and so inexpensive that clinics may dispense the preparation to charity patients without subjecting themselves to huge expenditures of money.

While the method of my invention may be utilized for the purpose of increasing the therapeutically potent materials obtained from animal material, such as glands, tissues, etc., the disclosure of the method, constituting a part of this invention is limited to the treatment of raw liver for the purpose of increasing the available therapeutically potent material contained in liver and employed in the treatment of anemia.

Generally stated, our method consists in taking a selected form of gland or tissue, weighing out a predetermined amount of the same, and passing it through a device, for example, a meat grinder to finely divide or mince the same. Such finely divided tissue or gland is placed in a container having therein an antiseptic in solution with water and an acid. Instead of acid, we may use any chemical which will produce a favorable autolytic reaction in respect to the hydrogen ion concentration, or any chemicals which produce a favorable medium for autolysis.

The container is then placed in an incubator, the temperature of which is maintained at approximately body temperature so that autolysis or enzyme action may take place. The antiseptic is added in order to prevent putrefaction of the tissue or the gland and the acid or other chemical is employed to give a (pH) that will be conducive to active autolysis, enzyme action, or in other words self digestion.

During the process of autolysis, the aforementioned potential supply of heretofore unavailable potent materials are rendered available. The longer the autolysis is permitted to go on the more these materials are formed.

In the light of prior scientific knowledge, we have drawn the conclusion that the preformed products which are present and available in beef liver, and available in larger quantities in calf's liver, are the end products of enzyme action. Therefore, if autolysis or enzyme action is permitted to go on under such conditions that putrefaction will not take place, the end products available for therapeutic action may be greatly increased.

After the autolysis is complete, the resultant mixture is concentrated by distillation, preferably under reduced pressure, so as to drive off

the antiseptic and the water. The undistilled residue may be filtered or not, as desired. In case the residue is filtered, the residue of the filtration, i. e., the undigested materials are discarded. To the undistilled residue, whether filtered or not, a preservative, such as alcohol may be added. If it is desired to make the preparation palatable, flavoring, such as peppermint, may be added.

In the treatment of liver by our method, we take fresh liver, beef liver being preferred since it is inexpensive, and grind it in a meat grinder to finely divide the same. This ground liver is then placed in a container having water, hydrochloric acid and chloroform therein, in the proportions of about 200 grams of liver, approximately 5 c. c. of chloroform, 2 c. c. concentrated hydrochloric acid, and 1000 c. c. of water. These proportions of hydrochloric acid and water give the proper degree of acidity or (pH) which is conducive to active autolysis. The chloroform is added as a preservative which permits the autolysis to go on but prevents putrefaction of the liver.

The (pH) of the solution which is favorable to active autolysis may vary from pH 2 to 7.5, but the most favorable pH is between pH from 4.5 to 7. The (pH) values favorable for active autolysis may be found in recognized text books, for example, see Wells' Chemical Pathology, 5th edition, pages 66 through 72. The extent to which any material may be autolyzed depends on the dilution of the autolyzing solution. The greater the dilution, the further the material will autolyze before the solution is saturated with amino-acids. For practical purposes, such a dilution is preferred that will require the least expense in evaporating water, to concentrate the autolyzed material, for a given potency.

The container is then placed in an incubator, the temperature of which is maintained at approximately 37° C. for a period averaging from 10 days to two weeks. During this period, the liver is broken down by self digestion, and the degree of completeness of such action may be determined by chemical analysis. The degree of completeness may be ascertained by determining what percentage of nitrogen is present in the form of protein and in the form of amino-acid, or end products.

The material which has thus undergone autolysis is concentrated by distillation under reduced pressure to drive off the chloroform and the water. It is preferred to concentrate the preparation under reduced pressure because the distillation at atmospheric pressure or higher, may raise the temperature of the preparation to a point which would destroy the beneficial elements or materials therein.

If desired, the concentrated residue may be filtered to remove the undigested portions of the liver. However, it has been found in practice that the unfiltered concentrate may be given to patients without impairing its therapeutic action.

To preserve the concentrate, alcohol may be added. Such a concentrate tastes very much like beef broth and has a slight after-taste similar to strong cheese. This after-taste may be avoided by adding flavoring, such as peppermint, to the concentrate.

In the treatment of liver as above described, it will be appreciated by those skilled in this art, that autolysis will not go on to completion because the water will become saturated with the end products such as, amino-acid. When sat-

uration takes place, a chemical equilibrium prevents further autolysis. The autolyzing material, in order to be autolyzed to completion or nearly so, may be dialyzed so as to prevent saturation or chemical equilibrium. If autolysis and dialysis are employed, the mixture of ground or minced liver, the water, hydrochloric acid, and the chloroform is placed in a container which is divided into two chambers separated by a partition, in which partition there is placed a dia-phragm of a material, such as parchment, which permits the amino-acid, or end products, to pass from the chamber in which autolysis is taking place to the other chamber. In this manner the autolysis may be carried out to completion.

From the above description it will be apparent to those skilled in the art that the method herein set forth for the treatment of liver not only renders available the preformed therapeutically potent material in the liver, but also produces large quantities of therapeutically potent material in form available for use and which was heretofore unavailable, and that this production of potent material is accomplished by autolysis of the liver itself wherein the autoic action is carried to completion or substantial completion.

It has been found that the treatment of beef liver, in the manner described above without dialysis, produces a preparation having more than five times the amount of potent material than can be obtained from the equivalent amount, by weight, of raw or partially cooked calf's liver. And this was so even though autolysis was far from complete.

Portions of autolyzed liver preparation after partial concentration under reduced pressure, have been fed by mouth to previously untreated cases of pernicious anemia, showing classical clinical features with symptoms indicating cord changes, typical blood picture and a chlorhydria. Reticulocyte responses characteristic of the treatment of pernicious anemia with potent material varying from 10 to 16% followed the oral ingestion of the equivalent of 500-750-800 grams of liver respectively in cases studied. The following chart summarizes the finding, in one of these cases, of the reticulocyte response to autolyzed liver.

Time	Reticulo-cytes percent	Grams autolyzed liver fed
1st day	1.0	60
2nd day	.5	150
3rd day	2.0	300
4th day	1.0	300
5th day	1.5	-----
6th day	3.0	-----
7th day	7.0	-----
8th day	13.0	-----
9th day	9.0	-----

A comparison of the above chart, the reticulocyte responses and the grams of autolyzer liver fed to the patient, to the amounts of liver reported in literature necessary to invoke a maximal reticulocyte response, shows that autolysis will materially increase the potency of liver preparations.

While the concentrate described above is an extract in liquid form it is to be understood that the potent materials thereof may be removed by well known processes, and put up in powdered form. The preparation made in accordance with this invention may be adapted for taking by mouth or by intramuscular injection.

The fraction G referred to herein may also be

obtained from the preparation resulting from liver treated by our method by a simple chemical process. To obtain fraction G it is merely necessary to treat the concentrated autolyzed preparation with absolute alcohol. The active part, which is insoluble, precipitates out.

In the treatment of certain kinds of tissue, to produce therapeutically active preparations, autolysis may be made more active by adding certain inorganic substances, such as for example, manganese chloride.

Having thus described our invention, it is to be understood that only such limitations shall be placed on the invention as are imposed by the prior art and the appended claims.

What we claim as new and desire to secure by Letters Patent is:

1. The method of increasing the anti-anemic properties of liver by at least 2.5 times the amount of such properties contained therein, that consists in autolyzing fresh liver in a solution at about body temperature and a pH favorable for active autolysis for such a length of time that the increase in the amino-acid content of the solution reaches a substantially constant level.

2. A method of increasing the amount of potent materials in raw liver by at least two and one-half times as determined by the amount of raw liver required to produce maximal reticulocyte response in pernicious anemia, that consists in autolyzing liver in an antiseptic acid solution having a pH favorable to active autolysis, and continuing such autolysis, to such a degree of completeness that the solution is substantially saturated with amino-acids.

3. The method of increasing the anti-anemic properties of liver to at least 2.5 times the amount of such properties contained in an equal amount of raw liver that consists in autolyzing fresh liver in a solution having a pH favorable to active autolysis for such a length of time that such increase is effected as determined by biological assay.

4. The method of increasing the anti-anemic properties of liver by at least 2.5 times that consists in autolyzing fresh liver in an antiseptic solution having a pH favorable for active autolysis and continuing such autolysis to such a degree of completeness that such increase of properties is attained as determined by the biological assay test for potency.

5. An anti-anemic preparation having a potency at least 2.5 times the potency of raw liver from which the preparation is made, comprising a concentrate derived from liver autolyzed in a solution having a pH favorable for active autolysis and for such a length of time that the amino-acids reach a substantially constant level.

6. The method of increasing the therapeutically potent material available in raw liver, which consists in placing raw liver in an acid solution containing an antiseptic and having a pH value within the limits of pH 2 to pH 7.5, promoting autolysis by maintaining the temperature of the solution at approximately 37° C., and continuing the autolysis until the amino-acid content in such solution has reached a substantially constant level.

7. The method of increasing the therapeutically potent material contained in raw liver by at least 2.5 times, which consists in mincing raw liver by grinding or otherwise, placing the minced liver in an aqueous solution of hydrochloric acid and an antiseptic in the proportions of approximately 200 grams of liver, 1,000 cc. water, 2 cc. concen-

trated hydrochloric acid, and 5 cc. of an anti-septic, such as chloroform, promoting active autolysis of the liver within the solution by maintaining the solution at approximately 37° C. and continuing the autolysis for such a period that the therapeutically potent material within such solution is increased by at least 2.5 times.

8. A method of preparing anti-anemic material from liver without loss of the effective anti-anemic properties contained in the original liver from which the material is made, which consists in placing raw liver in an acid solution containing an antiseptic and having a pH value within the limits of pH 2 to pH 7.5, promoting autolysis of such liver by maintaining the solution at approximately 37° C., and continuing the autolysis until the amino-acid content of the solution has reached a substantially constant level.

9. A method of increasing the yield of anti-

anemic material which can be derived from raw liver which consists in placing raw liver in an acid solution containing an antiseptic and having a pH value within the limits of pH 2 to pH 7.5, promoting autolysis of such liver by maintaining the solution at approximately 37° C., and continuing the autolysis until the amino-acid content of the solution has reached a substantially constant level.

10. An anti-anemic preparation containing at least as much of the anti-anemic properties as was contained in the original liver from which it was made, comprising a concentrate derived from liver autolyzed in a solution having a pH favorable for active autolysis and for such a length of time that the amino-acid content has reached a substantially constant level.
